US00D863573S

(12) **United States Design Patent** (10) Patent No.: **US D863,573 S**
(45) Date of Patent: **** Oct. 15, 2019**

(54) **ELECTRICAL NERVE STIMULATOR**

(71) Applicant: **OMRON HEALTHCARE Co., Ltd.**,
Muko (JP)

(72) Inventors: **Tamaki Ito**, Muko (JP); **Tsuyoshi Oghara**, Muko (JP); **Gen Suzuki**, Kamakura (JP); **Takashi Shigeno**, Tokyo (JP); **Kazuya Andachi**, Tokyo (JP)

(73) Assignee: **OMRON HEALTHCARE Co., Ltd.**,
(JP)

(**) Term: **15 Years**

(21) Appl. No.: **29/642,811**

(22) Filed: **Apr. 2, 2018**

(30) **Foreign Application Priority Data**

Oct. 3, 2017 (JP) 2017-021901

(51) **LOC (12) Cl.** **28-03**

(52) **U.S. Cl.**

USPC **D24/200**

(58) **Field of Classification Search**

USPC D24/200, 186-187, 168, 214-215

(57) **CLAIM**

The ornamental design for an electrical nerve stimulator, as shown and described.

DESCRIPTION

FIG. 1 is a perspective view of an electrical nerve stimulator showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines illustrate structure or features which form no part of the claimed design.

1 Claim, 4 Drawing Sheets
